COMBINED FRONT CONTROL PANEL AND GRILL FOR AN AIR CONDITIONER

Henry Dreyfuss, South Pasadena, Calif., assignor to
Whirlpool-Seeger Corporation, St. Joseph, Mich., a cor-
poration of Delaware

Application March 22, 1956, Serial No. 40,721

Term of patent 14 years

(Cl. D62—4)

Fig. 1.

Fig. 2.

Fig. 3.

Figure 1 is a perspective view of a combined front control panel and grill for an air conditioner showing my new design, with the control cover panel in closed position;

Figure 2 is a side view thereof; and

Figure 3 is a perspective view thereof with the control cover panel in open position.

I claim:

The ornamental design for a combined front control panel and grill for an air conditioner, substantially as shown.
